UNITED STATES PATENT OFFICE.

RUDOLF HARM, OF BERLIN-SCHONEBERG, GERMANY.

SUSPENSION DEVICE FOR WALL CHARTS.

Application filed November 28, 1925, Serial No. 72,027, and in Germany December 7, 1927.

The invention relates to a suspension device for wall charts, maps and the like and more specifically to suspension devices of this description constructed as hollow rollers.

5 Whereas heretofore the chart, map or the like was rolled up and down through a slit in the hollow roller by means of a winding device provided at the end of the roller, the present invention consists in the upper rod 10 of the chart being composed of two folding parts which, when closed, form the roller.

The invention further consists in the suspension string or other device being connected to the folding parts of the upper rod 15 of the chart, etc. in such manner that the weight of the chart by hanging causes an automatic closing of the folding parts. Hereby the chart can be secured at the top 20 between the folding parts and at the bottom to the rolling up rod which, when the chart is rolled up or partially unrolled, can be lodged in the hollow roller.

In the event of the hanging device in accordance with the invention being used 25 for exhibiting consecutive single maps or charts, the latter are divided by intermediate rods which can be introduced into the folding roller when single charts or maps or parts thereof are exhibited.

30 In the applications of the invention shown in the drawings

Fig. 1 shows a rolled up chart with suspension device,

Fig. 2 the same device with folding part 35 opened,

Fig. 3 the partially and Fig. 4 the entirely unrolled, chart.

Figs. 5, 6 and 7 are lateral views of Figs. 1, 2 and 4.

40 Fig. 8 shows an arrangement for exhibiting four single charts or maps.

Fig. 9 shows the connection of these single charts and

45 Figs. 10 and 11 the mode of suspension when exhibiting the single charts.

Fig. 12 shows another arrangement of the single charts.

50 Figs. 13, 14, 15 and 16 elucidate in this connection the mode of exhibiting the charts singly.

The arrangement shown in Figs. 1 to 7 may be adapted for exhibiting one or two

maps or charts, whereby one is pasted to the back of the other.

The case, which at the same time replaces 55 the upper holding bar, consists of two folding parts of card-board, tin or the like, jointed together, of which the semi-cylindrical case *a* is adapted to receive the chart *b*, whereby the cover *c*, which is likewise semi-cylindrical, closes the case *a* when the chart is put 60 away or hung up.

The locking device *d* visible at both ends is actuated directly by pulling the string *e* and in such manner that the cover *c* and the 65 case *a* close tightly together, thus forming a cylindrical case or holding means *a*—*c*. When the chart is rolled up, the string *e* can be wound around the case by means of keeper *f* and secured elastically to the button 70 *g*. As a result of the cooperation of *d* and *e* this quick closing effects a secure locking of the case *a*—*c* in its entire length.

On the other hand in hanging up the chart, the case closes automatically by its 75 own weight hanging on the string. For this reason it makes the neat impression of a one-piece bar. The point of suspension of the chart is relieved by means of a vice-action of the case parts *a* and *c* clamping 80 the chart between them. The said point of suspension is pasted, as shown in Fig. 7 between two strips of linen *h* hanging down from the jointure of the case. At its lower end it is connected in a suitable manner with 85 a cylindrical cardboard tube *i* of correspondingly lesser diameter than the case *a*—*c*. The annular reinforcing pieces *k* at both ends not only serve here as guides for the chart *b* when being rolled up, but are 90 also for the purpose of rendering the case more dustproof at the ends.

The device is accordingly very simple to manipulate: The case, closed in Fig. 1 by means of string *e*, is opened by pulling the 95 keeper *f* and lifting the string *e* from the button *g*, as well as by winding up the string (Fig. 2). The lower shell *i* is removed together with the chart *b* in Fig. 3, and the case *a*—*c* automatically closed in Fig. 4 by 100 hanging up the entire outfit. On again unrolling the chart the case opens automatically, as soon as the device is finally taken down from its hanger and allowed to hang

down. The unrolling and closing is then effected in the reverse order of that above described for opening according to Figs. 3, 2 and 1.

5 The above described suspension and protective device can, nevertheless, be used for a large number of charts or maps exhibited in promiscuous order to the audience in succession and from the same position. In this 10 manner Figs. 8 to 11 show four charts of this description, Nos. 1 to 4, in an order in which the maps or charts on the same side as 1 and 2 or 3 and 4 appear opposite each other, whereas Figs. 12 to 16 show an arrangement of simple maps or charts one below the other.

In both cases it is advisable to equip the above described device with a weighting rod 7, which when the charts are not in use, can be 20 conveniently kept in the hollow rod *i*, and when in use is introduced into a socket formed by two strips of linen *m*, (Fig. 9) between the upper and the lower charts.

The plans, Figs. 10 and 11, on the one hand 25 and 13 to 16 on the other show the characteristic positions in which the entire chart or map hanging in the usual manner in Figs. 8 or 12 is successively to be brought. Here 30 the feathered arrows show the necessary looking direction of the audience, and the unfeathered arrows the movement of rods *i* and *l* and the chart *b*, which brings about the condition shown in the next figure.

In the simpler case (Figs. 1 to 11) the 35 lower tube *i* is introduced into the case first before and then behind the part of the chart *b* hanging down in the case and secured in its position by the case closing automatically by virtue of the weight of the whole. The 40 transition from chart 1 to chart 2 is performed by simply turning the entire chart around. In order to show chart 3 in the same vision as chart 2, the tube *i* is taken out of the case part *a* moved entirely around. 45 Chart 4 is then exhibited by turning the whole around.

The characteristic positions in Figs. 13 to 16 are designated and to be understood 50 in the same manner, only in this case the weighting rod *l* is lodged alternately in this manner with tube *i* in the case.

I claim:

1. A suspension device for wall charts, 55 maps and the like comprising two independent holding elements, one of said elements comprising two folding parts forming when closed a hollow cylinder.

2. A suspension device for wall charts, 60 maps and the like comprising two independent holding elements, one of said elements

comprising two folding parts forming when closed a hollow cylinder, and a suspending string connected with the folding parts of the upper element. 85

3. A suspension device for wall charts, 70 maps and the like comprising two independent holding elements, one of said elements comprising two folding parts forming when closed a hollow cylinder, and a suspending string connected with the folding parts of the upper element and adapted to close said folding parts automatically by hanging up the chart. 75

4. A suspension device for wall charts, 80 maps and the like comprising upper and lower independent elements, the upper element comprising two folding parts forming when closed a hollow cylinder, and the lower element comprising a rolling up rod upon which the map is rolled whereby the chart on one side is secured between the folding parts of the upper element and on the other side on the rolling up rod. 85

5. A suspension device for wall charts, 90 maps and the like comprising independent upper and lower elements, the upper element comprising two folding parts forming when closed a hollow cylinder and the lower element comprising a rolling up rod upon 95 which the map is rolled whereby the chart on one side is secured between the folding parts of the upper element and on the other side of the rolling up rod which, when the chart is rolled up is adapted to be placed in the hollow cylinder.

6. A suspension device for wall charts, 100 maps and the like comprising independent upper and lower elements, the upper element comprising two folding parts forming when closed a hollow cylinder and the lower element comprising a rolling up rod upon which the map is rolled whereby the chart on one side is secured between the folding parts of the upper element and on the other side on the rolling up rod which, when the chart is partially rolled up, is adapted to be placed in the hollow cylinder. 105

7. A suspension device for exhibiting consecutive single charts or maps comprising 110 independent upper and lower holding elements, the upper element comprising two folding parts forming when closed, a hollow cylinder, and intermediate elements each of which forms the folding part of two consecutive 115 charts whereby all said elements are adapted to be inserted into the hollow cylinder.

In testimony whereof I have affixed my signature.

RUDOLF HARM.
